UNITED STATES PATENT OFFICE.

BIRDORA H. WHITE, OF CHICAGO, ILLINOIS.

GARMENT-SUPPORTER.

1,281,110.

Specification of Letters Patent.

Patented Oct. 8, 1918.

Application filed May 8, 1916. Serial No. 96,188.

To all whom it may concern:

Be it known that I, BIRDORA H. WHITE, a citizen of the United States, residing at Chicago, in the county of Cook and State of Illinois, have invented new and useful Improvements in Garment-Supporters; and I do hereby declare the following to be a full, clear, and exact description of the invention, such as will enable others skilled in the art 10 to which it appertains to make and use the same.

This invention relates to garment-supporters, and more particularly to that type of garment-supporters, which, when in use, are 15 adapted to be suspended from such garments as corsets, corset-waists, waists, belts, or suspenders, in connection with which garments it is necessary to adjust the fastening devices to a desired position.

20 The object of my invention is to provide a simply constructed, easily operated and effective buckle, in which the elastic webbing of the garment supporting device, in connection with which it is used, is securely held 25 against withdrawal both by a sliding device around which it is passed, and a clamping member carried thereby, substantially as hereinafter fully described, and as particularly pointed out in the claims:

30 In the drawings:

Figure 1 is a front view of a fragment of a garment supporter showing my improvements applied thereto.

Fig. 2 is a front view of my improved 35 buckle detached from said supporter showing a slightly modified construction of the sliding element thereof.

Fig. 3 is a similar view of the preferred form of my invention.

40 Fig. 4 is a similar view of the same showing yet another modification of the sliding element thereof, with the clamping device removed.

Fig. 5 is a plan view of the blank from 45 which the sliding element of the preferred form of my invention is made.

Fig. 6 is a similar view of the blank from which the clamping device of the said preferred form is made.

50 Fig. 7 is an edge view of said clamping device separated from the buckle.

Fig. 8 is a vertical central section taken on the center line of Fig. 1.

Referring to the drawings, it will be 55 noticed that the body or supporting-frame of my improved buckle is rectangular. I prefer

to make this frame of one piece of wire bent so that its end portions form the upper horizontal stretch 3 of the frame and terminate in opposed relation at about the center of 60 width of the same.

Slidably mounted upon the vertical sides 1 and 2 of this frame is a vertically movable member, which, in the preferred form of my improved buckle, consists of a flat rectangular piece of metal, of a height approximately one-half that of the supporting-frame, and of such a width that its ends can be bent back upon itself to form vertical tubular guides 5 and 6, that are adapted to surround and slide freely up or down on the vertical sides of the body of the buckle. This vertically movable member is provided with a transversely elongated rectangular opening 14, the position of which is such that the transverse 70 stretch of metal 8 below it is wider than the transverse stretch above, which latter forms a spindle 7 upon which the knuckles 11, 11, of a hinged clamping-plate 9 are journaled. 75

The templet from which this plate 9 is 80 formed is shown in Fig. 6 of the drawings, and it will be observed that between the lugs from which knuckles 11, 11, are formed, the lower edge is provided with a depending portion which when said templet is reduced to 85 the proper shape forms a cam or pressure-foot 10, which, as shown in Fig. 7 of the drawings, corresponds somewhat in cross-section to the curvature of an evolute.

When the parts of my invention are properly assembled, as hereinbefore described and as illustrated in the drawings, the buckle is supported through the medium of a web of suitable fabric 17 whose lower edge is 90 sewed around the upper stretch 3, 3, of the body of the hook, and whose upper end is attached in any suitable manner to the hem or selvaged edge of a garment of any nature. The upper end 15 of a pendent strap or web 16 of elastic or other material 95 is then passed to the rear through opening 14 of the sliding member and then downward back of the buckle to and forward through the space between the lower edge of said sliding member and the lower bar 4 100 of the body of the buckle, from whence it hangs downward. When the said end 15 of web 16 is thus threaded through the buckle, clamping-member 9 is moved on its axis and cam 10 thereof is brought to bear 105 against and to clamp web 15 between the same and the lower horizontal edge of open-

ing 14. When this is done the greater the downward strain on web 16, the more firmly its upper end will be held.

The modified construction of the sliding element shown in Figs. 2 and 4 of the drawings is due to the substitution of wire for the metal plate construction thereof, shown in the drawings, and particularly in Fig. 5 thereof. In Fig. 2 of the same, the ends 10 of a suitable length of wire are brought into horizontal alinement to form the spindle on which the knuckles of clamping-member 9 are journaled and extending from said ends each branch of the wire is bent to form 15 hook-shaped guides (that are the equivalents of guides 5 and 6) which engage and are slideable on the vertical sides of the body of the buckle, and to provide an unbroken lower horizontal member 8 which is opposed 20 and is adapted to coöperate with the lower horizontal member of the body of the buckle to clamp the web of elastic in the same manner as the corresponding parts of the preferred form of my invention do.

The modification shown in Fig. 4 of the drawing is also the result of making the sliding member of wire. The only difference from the sliding member shown in Fig. 2 is that the wire is made to describe a trans- 30 versely elongated rectangular shape, and the ends of this shape are made to hook around the vertical sides of the body of the buckle to form the necessary guides therefor.

What I claim is:

35 1. A buckle comprising an open rectangular supporting-frame, a sliding member the lower edge of which is adapted to coöperate with the lower horizontal bar of said frame,

Copies of this patent may be obtained for five cents each, by addressing the "Commissioner of Patents, Washington, D. C."

the ends of which are provided with guides that engage the vertical side members of the supporting-frame, and which has a transversely elongated opening therein between said guides through which the web of a garment supporter is adapted to be passed, and movable means that are adapted to prevent the withdrawal of said web from said opening.

2. A buckle comprising an open rectangular supporting-frame, a sliding member mounted thereon having a transversely elongated opening, a clamping-member which has lugs that are pivotally connected to said sliding member above said opening, and the lower edge of which is adapted to engage the web or strap of a garment-supporter to prevent its withdrawal.

3. A buckle comprising an open rectangular supporting-frame, a sliding member the lower edge of which is adapted to coöperate with the lower horizontal bar of said frame, 60 the ends of which are formed into guides that slide on the vertical sides of the same and which has a transversely elongated opening which is located nearer its upper edge than its lower edge, and a clamping 65 member which has lugs that are pivotally connected to said sliding member above said opening and which, between said lugs, substantially corresponds in cross-section to an evolute and is adapted to engage and clamp 70 the web of a garment-supporter passed through said opening against withdrawal.
